LIQUID SEPARATING LADLE

Richard H. Bair, Camp Hill, Pa.

Application May 4, 1956, Serial No. 41,350

Term of patent 14 years

(Cl. D44—29)

Figure 1 is a side elevational view of a liquid separating ladle, showing my design,

Figure 2 is a view in front elevation of the ladle,

Figure 3 is a top plan view, partly in section; and

Figure 4 is a partial sectional view along the line 4—4 of Figure 3.

I claim:

The ornamental design for a liquid separating ladle, as shown.
